TENTER CLIP

Philibert Deck, Zurich, Switzerland

Application August 30, 1949, Serial No. 113,080
In Switzerland January 13, 1949

2 Claims. (Cl. 26—62)

1

Clamps as parts of a tensioning chain are known, their purpose being to grip the edges of textile materials, e. g., fabric webs, between a fixed and a moving clamp, so tensioning the material. The moving part of the clamp is, in order to grip the textile fabric firmly, provided with a kind of knife-edge. Spike boards are likewise known as components of a tensioning chain, their purpose being to grip the edges of the textile material and thus to tension the latter.

In a known type of tensioning chain in which both clamps and spike or needle boards are provided so that either, as desired, may be used for tensioning purposes, the following drawbacks are noted:

When the clamps are used for tensioning purposes, the spike or needle boards are unprotected and the textile material may easily, when being inserted in the clamps, or even after being so inserted, inadvertently come in contact with the spikes of the spike boards as a result of insufficient initial tension. The fabric is consequently damaged or the spikes are bent. In addition, the danger exists that the fingers of the operator may be injured.

When, on the other hand, the spike or needle boards are used as the tensioning means, the movable, suspended portion of the clamps, which portion is usually fairly heavy so as to enhance its clamping action, bears with a sharp knife-edge on the fabric-supporting surface of the clamp, and as the chain links travel along the inevitable vibrations lift it from time to time, whereupon it drops back on the supporting surface, etc. These movements of the moving portion of the clamp relative to the fixed portion thereof cause wear and tear on the sharp edge of the moving portion, which is thus soon rendered unusable for clamping purposes.

Also known is a tenter clip in which the spike board is secured and a protecting arm is pivotally mounted on a bracket of the fixed member of the clamp, below the fabric-supporting surface of the clamp, which protecting arm is, when the textile fabric is tensioned by means of the clamp, swung into a position covering the spike board, but which, when the textile fabric is tensioned by means of the spike board, is swung upwards, in the course of which latter movement it moves the movable member of the clamp into an inactive position out of contact with the fabric-supporting surface of the clamp.

The novelty of the present invention resides in the fact that the supporting bracket of the fixed part of the clamp, bearing the spike board,

2

and the strap of the tenter clip are arranged on an extension of a link pin of a roller chain.

The drawing illustrates a tenter clip in accordance with the invention, in which:

- 5 Fig. 1 is a part section through a tenter clip and Fig. 2 is a similar section with certain parts changed in position as compared with Fig. 1.
- In the drawing, 1 is the strap of the tenter clip, 2 the connecting means to the next chain link 2a, 3 the moving clamp arm, 4 its knife-edge, 5 its feeler rollers and 6 the clamping plate constituting a portion of the fixed part of the clamp.
- To the fixed part of the clamp, below its fabric-supporting surface, a spike board 8 with spikes 15 is secured to a table 10 on a bracket 7, and a protective cover 12 is pivotally mounted on a pivot pin 11, the cover being intended in the known manner to cover the spike board 8 when the fabric is being tensioned by means of the clamp and to be swung upwards, bringing the moving clamp arm 3 into an inactive position out of contact with the fabric-supporting surface of the clamp plate 6, when the fabric is being tensioned by means of the spikes 9. The part 12a of the protecting arm covers the spike board 8 when said arm is swung downwards, while in its lifted position it presses on a projection 14 of the moving clamp arm 3. Part 12a is bent downwards (13) at its free end so as to cover off the spike board from the inner portion of the fabric.
- An operating member 15 is fitted to the protecting cover 12, by means of which the protecting cover may be raised and lowered by hand beyond the range of the spike board 8. A leaf-spring 16 20 locks the protecting cover 12 in its two operative positions, but not so powerfully as to prevent said cover from being swivelled from one to the other of its operative positions by appropriate pressure on the member 15. Two notches 17 and 18 25 of the protecting arm covers the spike board 8 when said arm is swung downwards, while in its lifted position it presses on a projection 14 of the moving clamp arm 3. Part 12a is bent downwards (13) at its free end so as to cover off the spike board from the inner portion of the fabric.
- An operating member 15 is fitted to the protecting cover 12, by means of which the protecting cover may be raised and lowered by hand beyond the range of the spike board 8. A leaf-spring 16 30 locks the protecting cover 12 in its two operative positions, but not so powerfully as to prevent said cover from being swivelled from one to the other of its operative positions by appropriate pressure on the member 15. Two notches 17 and 18 35 of the protecting arm covers the spike board 8 when said arm is swung downwards, while in its lifted position it presses on a projection 14 of the moving clamp arm 3. Part 12a is bent downwards (13) at its free end so as to cover off the spike board from the inner portion of the fabric.
- An operating member 15 is fitted to the protecting cover 12, by means of which the protecting cover may be raised and lowered by hand beyond the range of the spike board 8. A leaf-spring 16 40 locks the protecting cover 12 in its two operative positions, but not so powerfully as to prevent said cover from being swivelled from one to the other of its operative positions by appropriate pressure on the member 15. Two notches 17 and 18 45 of the protecting arm covers the spike board 8 when said arm is swung downwards, while in its lifted position it presses on a projection 14 of the moving clamp arm 3. Part 12a is bent downwards (13) at its free end so as to cover off the spike board from the inner portion of the fabric.

In accordance with the invention, the link pin 2b of each link 2a of the roller chain is extended in an upward direction. On the extension 2 of each chain link a clamp is secured by means of nuts 20. The bracket carrying the spike board is made integral with the strap.

What I claim is:

1. A tenter clip, for tensioning textile fabrics comprising a clamp with a movable member and

a fixed member, a bracket secured to the fixed member, a spike board attached to said bracket, a roller chain link with link pin, said link pin extended outwardly from said chain link to form an extension thereof, and a strap arranged on said extension of said link pin to hold the tenter clip to said roller chain link.

2. A tenter clip, for tensioning textile fabrics comprising a clamp with a movable member and a fixed member, a bracket secured to the fixed member, a spike board attached to said bracket, a roller chain link with link pin, said link pin extended outwardly from said chain link to form an extension thereof, and a strap arranged on said extension of said link pin to hold the tenter clip to said roller chain link, the said bracket being integral with said strap.

PHILIBERT DECK.
